UNITED STATES PATENT OFFICE.

CHARLES BRAND OFFICER, OF CLAREMONT, NEW HAMPSHIRE, ASSIGNOR TO SULLIVAN MACHINERY COMPANY, A CORPORATION OF MASSACHUSETTS.

MINING-MACHINE.

1,313,869.

Specification of Letters Patent.

Patented Aug. 19, 1919.

Application filed December 5, 1917. Serial No. 205,649.

To all whom it may concern:

Be it known that I, CHARLES B. OFFICER, a citizen of the United States, residing at Claremont, in the county of Sullivan and 5 State of New Hampshire, have invented certain new and useful Improvements in Mining-Machines, of which the following is a full, clear, and exact specification.

My invention relates to mining machines.

10 It has heretofore been proposed to provide a mining machine of the self-propelled short-wall type with an automatically movable sumping pan or frame slidably connected with the cutter bar and frame of the machine and adapted to support and 15 guide the machine during the sumping operation and to elevate the rear end of the same and thereby depress the point of the bar in the desired manner during the trans- 20 verse cut. In such devices a rear bottom plate has been provided on this sumping pan or frame which is adapted to be moved longitudinally relative to the shoe or bottom plate of the machine and to underlie 25 that shoe in all its operative positions, the same occupying a position under the front end of the shoe during the sumping operation and during the loading and unloading of the machine, and occupying a position 30 beneath the rear end of the shoe during the cut across the face.

My invention has for its object to provide improved means whereby a sumping pan of the character set forth may be used in connection with a mining machine with greater facility. A further and more specific object of my invention is to provide improved means whereby when said sumping pan is in its sumping or loading and unloading position the rear bottom plate on the same 40 may be disposed in a plane substantially flush with the plane of the bottom plate of the mining machine in such a manner that all difficulty arising from this plate digging 45 into the mine bottom, is effectually overcome at the same time that it is made possible for this plate, when desired, automatically to assume its supporting and tilting position beneath the rear end of the shoe of 50 the machine as the latter is summed in under the coal, preparatory to the transverse cut.

In the accompanying drawings I have shown for purposes of illustration one em-

bodiment which my invention may assume in practice, illustrating the same as applied 55 to a mining machine of a standard form.

In these drawings,—

Figure 1 is a side elevation of a mining machine with its sumping pan in its extended position occupied at the beginning 60 of the sumping operation and during loading and unloading.

Fig. 2 is a side elevation of the machine showing the sumping pan in its retracted position occupied as the machine completes 65 its sumping operation and as it moves across the face, certain parts here being omitted to facilitate illustration.

Fig. 3 is a perspective view of the sumping pan.

Fig. 4 is a transverse sectional view of the pan and machine taken substantially on line 4—4 of Fig. 2, the details of the interior of the mining machine being omitted to facilitate illustration.

In this illustrative construction it will be observed that I have shown a self-propelled mining machine frame 1 of standard form, the same being equipped with the usual cutter bar 2 carrying the cutter chain 3, and being provided with suitable feeding mechanism adapted to feed the bar in under the coal during the sumping operation, and to feed the same transversely across the face after its cut, these means being shown here- 85 in as including a driving sprocket 4 and a chain 5. As shown, this machine frame 1 is also provided with a shoe or lower bottom plate 6 forming a smooth surface on which the machine is adapted to slide upon the 90 mine bottom, and carries a longitudinally disposed skeleton sumping pan or frame 7 of the type forming the invention of one Jacob M. London, adapted to act as a guide and support for the machine frame and bar. 95 As usual in a London pan, this pan is slidably connected to the cutter bar 2 and provided with spaced transverse front and rear bottom plates 8 and 9 at its opposite ends, adapted to underlie and guide the machine 100 frame and cutter bar, respectively. As usual, suitable means, herein in the form of a pin 10 receivable in the pan and bar, are also provided to lock the pan in its ex- 105 tended position.

In my improvement, I have provided im-

proved means whereby the several plates on the sumping pan may, if desired, be disposed in the plane of the machine shoe in order to facilitate movement of the machine, these 5 means also, when desired, permitting one of these plates to be disposed in the plane of the shoe while the other is disposed beneath that plane and the rear end of the machine in such a manner as to tilt the bar. These 10 means may, obviously, assume various forms. In the illustrative form of my invention shown herein, however, it will be observed that the shoe 6 is cut away beneath the front end of the machine and provided with an 15 upwardly inclined edge 11. It will also be observed that at a point above and at either side of this inclined edge 11, but preferably slightly in front of the same, suitable means in the form of laterally extending pins 12 20 are provided on the side of the machine frame 1, adapted to coöperate with the reciprocatory sumping frame 7 so that either the rear bottom plate 9 thereof or the front bottom plate 8 thereof may be received in the 25 space thus formed beneath the front end of the frame of the machine 1 and in advance of the front edge 11 of the shoe 6. It will also be noted that the sides of the frame 7 are provided with suitable longitudinally 30 disposed slots or grooves 13 so that a relative movement may take place between the frame 7 and the pins 12, and that at their rear ends these grooves 13 communicate with short, downwardly inclined grooves 14, in 35 turn communicating with other horizontally disposed grooves 15 which are located at the extreme rear ends of the frame 7. Attention is here also directed to the fact that, as shown herein, the rear edge of the rear 40 bottom plate 9 on the frame 7 is provided with an inclined surface 16 adapted to coöperate with the inclined surface 11 on the shoe 6, as hereinafter more fully brought out, and that at the rear end of the frame 1 45 and on opposite sides of the same, laterally extending pins 17 are provided adapted to be received in the grooves 15 and coöperate with the pins 12 when the parts are in the position shown in Fig. 2.

50 In the operation of a mining machine equipped with my improved mechanism, it will be noted that in the extended position of the frame 7 shown in Fig. 1, *i. e.* that position which the parts occupy after the 55 withdrawal of the bar from the coal, during loading and unloading, and at the beginning of the next sumping cut, the rear bottom plate 9 of the frame 7 is disposed in the space beneath the front end of the frame 60 and in advance of the front edge of the shoe 6, with its inclined edge 16 in engagement with the inclined edge 11 of the shoe 6, the pins 12 then occupying the position shown in the short, horizontal slots 15. Obviously, 65 with the parts in this position the plate 9

will form a continuation of the shoe 6, the same being disposed substantially flush therewith and in the same plane as both the plate 8 and the shoe 6, so that as the machine is dragged over the mine bottom, as for instance during the operation of loading it onto the truck or unloading it therefrom, the same may move freely and without any digging up of the bottom. However, when it is desired to start a new cut, that is, to begin the next sumping operation, it will be noted that by removing the pin 10 the machine may be freely moved relative to the pan 7 in a well known manner by means of its sprocket 4 and chain 5, and that as a result of the operation of these elements, the machine will be so reciprocated relative to the pan. During this movement it will be noted that the inclined edge 11 of the shoe 6 will ride up over the inclined edge 16 of the plate 9 under the guidance of the pins 12 which simultaneously move in the inclined grooves 14 on the frame 7, so that the shoe 6 may pass over the plate 9 toward the position shown in Fig. 2. In this position, *i. e.* 90 the position of the parts at the completion of the sumping operation and during the transverse cut, the frame 7 is retracted and the parts are in position to make the transverse cut, the plate 9 then being disposed beneath the rear end of the shoe 6 in such a manner as to elevate the rear end of the machine and thus tilt down the tip of the bar, while the front plate 8 of the frame 7 is disposed within the space beneath the front end of 100 the frame 1 and in advance of the inclined edge 11 of the shoe 6. Obviously, after the completion of the transverse cut the parts will be automatically returned to the position shown in Fig. 1 as the machine is withdrawn from the cut, and may be locked in that position during loading and unloading by simply inserting the pin 10.

As a result of my improvement, it will be observed that not only is an entirely 110 smooth shoe provided effective substantially throughout the entire length of the machine when the sumping frame is extended and thus eliminating all difficulty with tearing up the bottom during transport, but that at 115 the same time it is possible for the sumping pan to function as a guide in its well known manner during the sumping operation and to act as a supporting and tilting means for the machine during its transverse cut. Attention is also directed to the fact that through the provision of my improved mechanism including the rear pins 17, the parts are held in the desired position when the sumping frame is retracted, and that 120 through the use of the pins 12 and 17 and their coöoperating grooves a sturdy construction is produced well adapted to withstand the rough usage to which such machines are 125 subjected in service. These and other ad- 130

vantages of my improved construction will, however, be clearly apparent to those skilled in the art.

While I have in this application specifically described one embodiment which my invention may assume in practice, it will be understood that the form of the same shown herein is used for purposes of illustration and that the invention may be modified and embodied in other forms without departing from its spirit or the scope of the appended claims.

What I claim as new and desire to secure by Letters Patent is:

15 1. In a mining machine, a machine frame having a cutter bar thereon, and means operatively connected telescopically with said frame including a member disposable in different longitudinal positions beneath the bottom of said frame or in the plane of the bottom thereof.

20 2. In a mining machine, a machine frame having a cutter bar thereon, and means operatively connected telescopically with said frame including a rear bottom plate disposable in different longitudinal positions beneath the bottom of said frame or in the plane of the bottom thereof.

25 3. In a mining machine, a machine frame having a cutter bar thereon, and means operatively connected telescopically with said frame including front and rear bottom plates disposable in the plane of the bottom of said frame.

30 4. In a mining machine, a machine frame having a cutter bar thereon and a shoe, and a sumping pan telescopically connected with said frame and having front and rear bottom plates, said plates and shoe being

35 adapted to be disposed in a single plane.

40 5. In a mining machine, a machine frame having a cutter bar thereon and a shoe, and a sumping pan telescopically connected with said frame and having front and rear bottom plates, said plates and shoe being adapted to be disposed in a single plane when said pan is in its extended position.

45 6. In a mining machine, a machine frame having a cutter bar thereon and a shoe, and a sumping pan telescopically connected with said frame and having front and rear bottom plates, said plates and shoe being adapted to be disposed in a single plane or in a plurality of substantially parallel planes.

50 7. In a mining machine, a machine frame having a cutter bar thereon and a shoe, and a sumping pan telescopically connected with said frame and having front and rear bottom plates, said rear plate being adapted to be disposed in the plane of said shoe and also in a parallel plane.

55 8. In a mining machine, a machine frame having a cutter bar thereon and a shoe, a sumping pan slidably connected to said bar

and telescopically connected with said machine frame and having a rear plate disposable in the same plane as said shoe, and means whereby said machine frame may be elevated as the same is moved relative to said pan.

5 9. In a mining machine, a machine frame having a cutter bar thereon and a shortened shoe, and a sumping pan telescopically connected with said frame and slidably connected to said bar and having a rear bottom plate disposable beneath said frame and adjacent the front edge of said shoe.

10 10. In a mining machine, a machine frame having a cutter bar thereon and a shoe, a sumping pan slidably connected to said bar and telescopically connected with said frame, and operative connections between said machine frame and sumping pan including a guiding member and a plurality of relatively inclined slots coöperating therewith.

15 11. In a mining machine, a machine frame having a cutter bar thereon and a shoe, a sumping frame slidably connected to said bar, and operative connections between said machine frame and sumping frame including a guiding member and a plurality of horizontal slots and an intermediate inclined slot for coöperating therewith.

12. In a mining machine, a machine frame having a cutter bar thereon and a shoe, a sumping frame slidably connected to said bar, and operative connections between said machine frame and sumping frame including a plurality of guiding members at opposite ends of said machine frame and a plurality of communicating slots disposed at different levels and formed in said sumping frame.

17 13. In a mining machine, a machine frame having a cutter bar thereon and a shortened shoe, and a sumping pan slidably connected to said bar and frame and having a bottom plate disposable in advance of the front end of said shoe, the bottom plate on said sumping pan being adapted to be disposed beneath the rear end of said shoe.

18 14. In a mining machine, a machine frame having a cutter bar thereon and a shortened shoe having an inclined front edge, and a sumping frame slidably connected to said bar and having a rear bottom plate provided with a coöperating inclined rear edge, said plate being disposable beneath said frame and with its inclined rear edge adjacent the front edge of said shoe.

19 15. In a mining machine, a machine frame having a cutter bar thereon and a shoe, a sumping pan engaging said bar and telescopically connected with said machine frame and having a rear plate disposable in the plane of said shoe, and means whereby said machine frame may be elevated as the same is moved relative to said pan.

20 16. In a mining machine, a machine frame

having a cutter bar thereon and a shortened shoe, and a sumping pan telescopically connected with said frame and engaging said bar and having a rear bottom plate disposed beneath said frame and adjacent the front edge of said shoe.

17. In a mining machine, a machine frame having a cutter bar thereon and a shoe, a sumping pan slidably connected to said bar and telescopically connected with said machine frame and having a rear plate disposable in the plane of said shoe, and means carried by said pan whereby said machine

frame may be elevated as the same is moved relative to said pan.

18. In a mining machine, a machine frame having a cutter bar thereon and a shortened shoe, and a sumping pan telescopically connected with said frame and shoe and slidably connected to said bar and having a rear bottom plate disposable beneath said frame and adjacent the front edge of said shoe.

15. In testimony whereof I affix my signature.

CHARLES BRAND OFFICER.
